IMMERSION STARTER FOR POOL-TYPE
DISCHARGE DEVICESEmil Rupp, Berlin-Frohnau, Germany, assignor
to General Electric Company, a corporation of
New YorkApplication October 31, 1935, Serial No. 47,694
In Germany November 8, 1934

2 Claims. (Cl. 250—27.5)

My invention relates to an improved immersion starter for pool-type discharge devices.

It is now known that an arc discharge between a mercury pool cathode and an anode spaced 5 therefrom can be initiated with great facility by means of an immersion electrode of a semi-conducting material such as silicon or tungsten carbide having its tip projecting below the surface of the mercury pool. While the nature of the 10 starting phenomenon is not entirely understood, it is found to differ fundamentally both in effectiveness and in amount of required starting current from that obtained by the use of a metallic filament projecting into the mercury such 15 as is shown, for example, in Bodde Patent No. 832,363.

In general, it is believed that the starting effect of the new immersion electrode depends in part upon the nature of the contact between its 20 surface and the adjoining mercury and, in part, upon the creation of a high potential gradient along the electrode body. Immersion starting, together with the theoretical considerations 25 which govern its operation are discussed in an article by J. Slepian and L. R. Ludwig appearing at page 693 of vol. 52 of the Transactions of the A. I. E. E. for June, 1933.

It is an object of the present invention to provide an immersion electrode characterized by requiring a lower starting current than those 30 previously employed and by greater freedom from starting variations.

An understanding of the further objects and 35 advantages of my invention may be obtained by referring to the following specification taken in connection with the accompanying drawing in which Fig. 1 illustrates an electric discharge device suitable for use with my invention, while Fig. 2 is a fragmentary section of the tube of Fig. 40 1 shown as embodying a preferred form of starting electrode.

Referring particularly to Fig. 1, I have shown a three-electrode discharge device comprising an envelope 1 which contains an anode 2 and a mercury pool cathode 3 adapted to cooperate in conducting an arc-like discharge through the tube. Starting of the discharge is accomplished by passing current through the lead-in connection 4 and the immersion electrode 5. This latter consists 50 essentially of a mixture of clay and graphite and has a thickness of say, 1 to 2 millimeters, and a length on the order of about 2 centimeters. When starting current of a few amperes flows from the immersion electrode into the mercury pool a main discharge will take place if there is

at the same time a positive voltage on the anode 2.

As a material for the construction of my improved immersion electrode I have found that graphite rods having a graphite content not in excess of 80 per cent and a complementary proportion of clay have many outstanding advantages. The graphite may vary from the maximum value stated down to a minimum of about 20 per cent, the composition being chosen to cause the specific resistivity to fall between about 100 10 and about 100,000 times that of mercury. While the electrode rod may assume various shapes, I prefer to have it pointed at the active end which is then immersed in the mercury to a depth of several millimeters. The depth of immersion may 15 be adjusted by corresponding adjustment of the quantity of mercury in the cathode pool.

Since an unpredictable quantity of the mercury will vaporize during operation of the tube and remain adhering to the envelope wall, undesirable variations in the starting current may 20 occur. In Fig. 2 I have represented a form of starting electrode by means of which this difficulty may be overcome. As illustrated, the graphite rod 6 is surrounded by a tube 7 of glass, 25 quartz, or a similar heat withstanding insulating material from which the rod projects very slightly, say a few tenths of a millimeter. Above the mercury the electrode comprises an exposed conductive portion consisting in the present instance of an enlarged extension 8 of the graphite core in combination with the clamp-like extremity of the conductor 4. The depending portion of the electrode projects downward a sufficient distance so that the core is exposed to the 30 mercury only below the surface thereof. This arrangement, which is applicable to other semi-conducting starting materials than graphite, has the advantage that effective starting can be accomplished with different depths of immersion 35 up to at least about 5 millimeters. For this reason variations in the mercury level fail to effect the required ignition current. Consequently, in the manufacture of such tubes accurate 40 adjustment of the cathode pool is unnecessary and the irregular condensation of the pool on the envelope wall plays only a subordinate part.

While I have shown a particular embodiment of my invention, it will of course be understood 50 that I do not wish to be limited thereto since many modifications in the structure may be made, and I contemplate by the appended claims to cover all such modifications as fall within the true spirit and scope of my invention.

What I claim as new and desire to secure by Letters Patent of the United States, is:—

- 5 1. In an electric discharge device, an anode, a mercury pool cathode and a starting electrode supported in cooperative relation with said cathode, said electrode comprising an exposed conductive portion above said mercury pool and a depending portion projecting below the surface of the pool during the normal operation of the device, said last-named portion consisting of an insulating sheath and a core of a semi-conducting material having a specific resistivity between about 100 and 100,000 times that of mercury, the core being substantially enclosed by the sheath and being exposed to the mercury only below the surface thereof.
- 10
- 15

2. In an electric discharge device, an anode, a mercury pool cathode and a starting electrode supported in cooperative relation with said cathode, said electrode comprising an exposed conductive portion above said mercury pool and a portion projecting below the surface of the pool during the normal operation of the device, said last-named portion comprising an insulating sheath and a core of semi-conducting material having a specific resistivity between about 100 10 and 100,000 times that of mercury, the core being substantially enclosed by the sheath but having a tip projecting therethrough into contact with the mercury below the surface thereof.

EMIL RUPP.
